(57) **CLAIM**

The ornamental design for "street light head," as shown and described.

DESCRIPTION

FIG. 1 is a top left rear perspective view of a street light head in accordance with my new design;

FIG. 2 is a front elevation view thereof, the rear elevation view being a mirror image thereof;

FIG. 3 is a top plan view thereof;

FIG. 4 is a bottom plan view thereof;

FIG. 5 is a right side view thereof; and,

FIG. 6 is a left side elevation view thereof.

The broken lines shown on the drawings depict environment only and form no part of the claimed design.
